UNITED STATES PATENT OFFICE.

PHILIP M. BIONDO, OF BROOKLYN, NEW YORK, ASSIGNOR OF ONE-THIRD TO JOSEPH MESSINA AND ONE-THIRD TO CHARLES CIRAVOLA, BOTH OF BROOKLYN, NEW YORK.

PENHOLDER AND PROTECTOR.

Application filed December 8, 1923. Serial No. 679,371.

To all whom it may concern:

Be it known that I, PHILIP M. BIONDO, a citizen of Italy (having taken out first United States citizenship papers), and a 5 resident of the city of New York, borough of Brooklyn, in the county of Kings and State of New York, have invented a new and Improved Penholder and Protector, of which the following is a full, clear, and exact 10 description.

This invention relates to pen holders and protectors and has for an object to provide an improved construction wherein the pen may be adjusted to a writing position and 15 to a protected or reserved position whereby the point cannot be engaged by the hand or cannot engage the clothes when the article is placed in the pocket.

Another object of the invention is to provide 20 a pen holder wherein the pen is mounted in a sliding member capable of adjustment to two positions, the sliding structure being associated with a protecting plate capable of covering the end of the pen 25 when not in writing position.

In the accompanying drawing—

Figure 1 is a top plan view of a pen holder, disclosing an embodiment of the invention.

Figure 2 is a side view of the structure shown in Figure 1 with one end broken away in vertical section for illustrating the construction.

Figure 3 is a transverse sectional view 35 through Figure 2, approximately on line 3—3.

Figure 4 is a view similar to Figure 1 but showing the pen and associated parts in their retracted position.

Referring to the accompanying drawing by numerals, 1 indicates a handle of any desired kind provided with a hollow extension 2 which may be of the same material as the handle or may be made of other material and secured in place. As shown in the drawing, the extension 2' is made integral with the handle 1 and fits in the hollow member 2. Preferably the front plate 4 is secured to the tubular guard 3. The 45 plate 4 does not cover the entire end of the tubular guard 3 but leaves the upper part exposed whereby the pen 5 may freely move back and forth over the plate 4. This pen is held in place by the resilient action of the 55 overlapping sections of the pen sleeve 6.

This sleeve is formed of a thin piece of metal coiled on itself so as to provide a body 7 as shown in Figure 3 and an underlapping section 7' whereby the pen 5 may be resiliently gripped therebetween.

By simply wrapping a piece of sheet metal in this way to form a tubular member, a simple but effective structure is presented whereby the pen 5 is firmly gripped but may be readily removed and re-applied at any time. The pen sleeve 6 at the inner end is rigidly secured to a cap 8 by solder or other desired means, said cap sliding on the hollow member 2. This cap is preferably provided with a bead 9 whereby it may be 70 readily grasped and moved back and forth for reciprocating the pen sleeve 6. In order that the pen sleeve 6 and, consequently, the pen 5, may be properly positioned or centered, the cap 8 is provided with a V-shaped extension 10 fitting into a similar shaped notch 11 as illustrated in Figure 1. This will prevent any accidental rotation of the parts when the pen is exposed as shown in Figures 1 and 2.

When it is desired to place the device in the pocket or some other desired place, the cap 8 is grasped and pulled to the position shown in Figure 4. This action will cause the pen sleeve 6 to retract the pen 5 so that it will be protected by the tubular guard 3 and also the clothes will be protected against the pen in case the device is placed in the pocket. The pen may be quickly and easily moved to its outer position by forcing the cap 8 back to the position shown in Figure 1.

What I claim is:—

1. A pen holder and protector, comprising a handle, a tubular member extending from one end of the handle, a tubular pen guard secured to the front end of said tubular member and surrounding the tubular member for an appreciable part of its length, a pen sleeve surrounding said tubular member and positioned to reciprocate in said guard, said sleeve having an overlapping portion presenting clamping members for a pen, and a hand operated member connected to one end of said pen sleeve, said hand operated member being formed with means readily grasped whereby the sleeve and pen carried thereby may be moved so that the pen will be beneath the pen guard when the parts are in one position and pro-

jecting therefrom when the parts are in a second position.

2. A pen holder and protector, comprising a body having a forwardly extending portion, a guard connected with said forwardly extending portion, said guard being formed with a notch at one end, a pen receiving member carried by said forwardly extending portion, a cap secured to said pen

receiving member, said cap having an annular bead, and a projection co-acting with the projection in the guard for causing the pen to be properly positioned when the parts are in one position, said cap being adapted to be moved to a second position 15 for shifting the pen to a position beneath said guard.

PHILIP M. BIONDO.
